UNITED STATES PATENT OFFICE.

GEORGE J. WEBER, OF BOONVILLE, MISSOURI.

BRICK-MACHINE.

SPECIFICATION forming part of Letters Patent No. 309,589, dated December 23, 1884.

Application filed July 30, 1883. (No model.)

To all whom it may concern:

Be it known that I, GEORGE J. WEBER, a citizen of the United States, residing at Boonville, in the county of Cooper and State of Missouri, have invented certain new and useful Improvements in Brick-Machines, of which the following is a specification.

The principal objects of my invention are, first, to provide means whereby the return or backward stroke of the feeder and its accessories is produced by compressed air or vacuum, and, secondly, to improved means for cushioning the reciprocating parts in such a manner that the machine will not be subjected to sudden shocks.

In order that my invention may be fully understood, I will proceed to describe it with reference to the accompanying drawings, in which—

Figure I is a detail sectional elevation of a brick - machine with my improvements attached. Fig. II is a side elevation on a larger scale of the link end of the piston-rod and air-cylinder. Fig. III is an end elevation of the machine.

1 represents a suitable gear-wheel for driving a sheave, 2, carrying anti-friction rollers 3, which impinge against the angular or inclined face of a rocking lever, 4, which is flexibly connected to a jointed plunger, 5, carrying the feeder 6.

Connected to the jointed plunger 5 is a bell-crank lever, 7, journaled in a suitable bracket, 8, and connected at its lower end to a vacuum-chest through the medium of a link, 9. This vacuum-chest consists of an outer cylinder, 10, which slides up and down on a stationary core, 11. The top of the cylinder 10 is provided with a check-valve, 12, of any suitable construction, for preventing the admission of air during the ascent of the cylinder, while allowing any air which may have entered through the cock 13 to escape during its descent. The cock 13 is for the purpose of regulating the quantity of vacuum formed in the chest. Thus it will be seen that the parts are by this means cushioned on the forward movement of the plunger 5, and as soon as the roller 3 has passed the summit of the incline on the lever 4 the vacuum will retract the plunger to its normal position. The backward motion

of the plunger is cushioned by the lower end of the cylinder 11 entering an annular air-chamber formed by an annular collar, 14, surrounding the lower portion of the core 11. 55 This air-chamber is provided with a check-valve, 15, for confining the air during the descent of the cylinder 11, and for admitting air to prevent the forming of vacuum on its ascent. This cylinder is also provided with a regulating-cock, 16, for permitting a requisite quantity of air to escape to prevent a too sudden stoppage and consequent rebounding of the plunger.

Secured to the sheave 2 is a wrist-pin, 17, 65 mounted and turning in a block, 18, sliding in a link, 19, in the end of the plunger 20, and carrying a piston-rod, 21, the head of which works in an air-chest, 22. This chest or cylinder is provided at each end with a check-valve, 23, and regulating-cock 24, for the purposes already explained. The press-blocks 25 70 26 are operated by massive arms 27 27, fulcrumed to uprights or standards 28, and connected at their rear ends by toggle-levers 29 75 29, pivoted to a block, 30, to which the operating-piston 20 is fulcrumed. The press-blocks are loosely pivoted to the shorter ends of the arms 27, the lower one being guided in its path by its head working in an opening in the 80 bed-plate 30, which forms the mold, and the other guided by a cross-bar, 31, working in vertical grooves in the corners of the uprights 28.

32 is a lug secured to the press-block 25, and 85 33 a spring-catch secured to the press-block 26, and working in a guiding-strap, 34. This constitutes the mechanism for elevating the brick out of the mold, its operation being as follows: When the rear ends of the arms 27 are 90 drawn together, the tendency is to throw open the press-blocks; but by reason of the catch 33 being in engagement with the lug 32, and the greater weight of the rear ends of the arms 27, the upper press-block, 25, will be elevated, carrying with it the lower one. At this time the feeder 6 moves forward, carrying the brick from between the press-blocks, the forward movement of the feeder also swinging the upper press-block, 25, on its pivot, which disengages the catch 33 and permits the lower block 95 to drop. The new charge of clay, which is con-

tained in a mortise in the feeder 6, then drops into the mold, and the feeder returns to its normal position, and by means of the springs 35 returns and holds the guide-bar 31 to its seat. It will be seen that while the lever 20 is moving forward or backward the feeder 5 6 will be in its retracted position and out of the way of the press-block, and that while the lever 20 is in its forward position and the press-blocks raised the feeder 5 6 moves forward and returns to its normal position before the retraction of the lever 20 commences.

It is obvious that the relations of the valves and cocks may be changed at will for compressing air or forming a vacuum without departing from the spirit of my invention.

Having thus described my invention, the following is what I claim as new therein and desire to secure by Letters Patent:

1. In a brick-machine, the combination, with suitable mechanism for forcing the feeder forward, of a vacuum-pump for returning it.

2. In a brick-machine, the combination, with the feeder and suitable mechanism for forcing it forward, of a vacuum-pump for the purpose explained, having a check-valve and regulating-cock, as and for the purpose set forth.

3. In a brick-machine, the combination, with the feeder and suitable mechanism for operating it, of an air-cylinder having a regulating-cock for preventing shock, and a check-valve, as and for the purpose set forth.

4. In a brick-machine, the combination, with a sheave carrying an anti-friction roller, and a vibrating lever having a cam-shaped head, connected to the feeder, for moving it in one direction, of an air or vacuum pump for returning it, as set forth.

5. In a brick-machine, the combination, with the press blocks and suitable toggle-levers connecting them, of an operating-lever connected at one end to the toggle-block, and at the other to the main sheave through the medium of a

wrist-pin mounted in a block sliding in a link formed in the aforesaid operating-lever, as set forth.

6. In a brick-machine, the combination, with the driving-sheave and a plunger connected thereto through the medium of a wrist-pin and a block sliding in a link in said plunger, of a double-acting air-cylinder whose piston is connected to the aforesaid sliding block, as and for the purpose set forth.

7. In a brick-machine, the combination, with the driving-sheave and plunger, having mechanism, substantially as herein described, for connecting them, of an air-cylinder having a cock and valve at each end, as and for the purpose set forth.

8. In a brick-machine, a feeder having spring-hooks, as and for the purpose set forth.

9. In a brick-machine, the combination, with a main sheave carrying an anti-friction roller, and a vibrating lever having a cam-shaped head for forcing the feeder forward, of a vacuum or air pump for returning it, as set forth.

10. The combination, with the feeder of a brick-machine, of a vacuum-pump consisting of a stationary core and sliding casing or cylinder provided with a suitable valve and regulating cock, as and for the purposes set forth.

11. A vacuum-pump and compressed-air cylinder constructed substantially as herein described, which consists of a central core having an enlarged base provided with an annular groove surrounding said core, and having a suitable valve and cock, and a sliding casing or cylinder provided with a valve and cock, adapted to slide over the central core and enter the annular groove, as and for the purposes set forth.
